UNITED STATES PATENT OFFICE.

CARL E. SCHMIDT, OF DETROIT, MICHIGAN.

HIDE AND METHOD OF TREATING THE SAME.

1,118,813.

Specification of Letters Patent. Patented Nov. 24, 1914.

Application filed March 31, 1913, Serial No. 757,970. Renewed August 3, 1914. Serial No. 859,263.

To all whom it may concern:

Be it known that I, CARL E. SCHMIDT, who am a citizen of the United States of America, residing in Detroit, Wayne county, Michigan, have invented new and useful Improvements in Hides and Methods of Treating the Same, whereof the following is a full, clear, and exact description, such as will enable others skilled in the art to 10 which it pertains to apply and use the same, reference being had to the drawings, which form a part hereof.

The invention relates to the stretching and drying of hides and skins during their treatment and preparation for marketing as leather ready for use, and has for its object an improved method of handling and working, whose purpose is to avoid the objectionable features of unevenness of product and 20 trimming waste incident to the process as now followed, in which the skins are stretched or "put out" on smooth tables, thereafter removing the hides or skins and stretching them out on frames, where they 25 are tacked or held in place by pins or by toggles until the leather is dried. This method is objectionable in that no account is or can be taken of the variations in the quality and thickness of the hide, as for example, between the relatively tough and thick part 30 near the center and the "flank" portions, where the hide is thinner and more tender. Furthermore, when this method of treatment is followed, there is produced all around the 35 edge of the hide a series of tack holes, between which there are located unevenly stretched portions of the leather, which it is necessary to cut off and discard either at the tannery or when the hide is cut up for its 40 special use.

In the drawings: Figure 1 is perspective of a setting-out board with a hide stretched thereover. Fig. 2 is a sectional elevation, in exaggerated proportions as to thickness, of 45 the board, the hide, and the interposed mucilaginous film.

The avoidance of this waste, which experience shows amounts to about five percent., and involves leather otherwise just as good as the portion that is saved as well as the securing of greater uniformity in the quality of the finished leather, is the object of this invention, in the carrying out of which I employ a flat surface A of either 50 wood, metal or glass, or even paper or cardboard, which is coated, just before the hide

is stretched thereover, with a film of adhesive or mucilaginous substance B such as glue, gelatin, dextrin, silicate of soda, glucose, Irish moss, glycerin or soap, and over 55 which the hide C is then stretched to the degree desired, and preferably with the "grain" side downward, after which the then exposed surface of the leather is worked, either by the operator's hand or by 60 the application of a glass or metal tool, until it is flattened against the supporting surface A to the degree and with the evenness required, the operator gradually working toward the edge portions, which are the last 65 to be pressed against the coated surface A. The "flank" portions F of the hide, which are normally the thinnest and most yielding parts, can thus be "worked" somewhat 70 thicker by partially rolling thereinto and 75 thereover from the adjacent thicker portions of the leather, while still wet and plastic, so that its mass is finally brought very near to the standard of the remaining portions of the hide. Although both the hide and the 80 applied mucilaginous or adhesive substance on the finishing surface or table are still wet by the time this "working" has been completed, I have found that the union thus secured between the hide and the adjacent 85 portions of the table surface is such as to hold the hide in the degree of tension and uniformity of quality to which it has been brought while it is drying, so that the hide when dried and ready to be moved is of the 90 same size and even quality left by the worker. Moreover, this grain side being protected from the light during drying gives 95 a surface of exceptional uniformity of color or shade. When dry or nearly so, the hide is easily stripped from the finishing surface, and the character as well as the proportion of the adhesive substance used is such as to be of no objectionable effect on the finish of the leather or any subsequent treatment to 100 which it may be desired to subject it, and in some instances actually beneficial. This process also results in making all of the leather to the extreme margin available, instead of the previously perforated edge portion which had to be cut off.

I desire it clearly understood as within the scope of my invention to use any adhesive or mucilaginous medium for the purpose stated, whether herein specifically named or not, since particular substances may be found specially adapted for certain condi-

tions. And while I have described the coating of the finishing surface with the adhesive or mucilaginous substance, the soaking of the leather therewith or therein before putting it, thus allowing it to dampen the surface over which it is spread out could of course, easily be substituted therefor.

The advantages of my invention result from the greater uniformity of thickness in 10 the different portions of the treated hide and from the desirable surface condition of the grain side of the dried hide. There is much less loss in working the hide up into leather and the surfaced grain side of the leather 15 is in excellent condition for further treatment and use.

By working the grain side of the leather down on the supporting surface, this face of the leather is impressed with the character 20 of the surface. When the surface is smooth, the leather, drying in intimate contact with it, assumes a similar smoothness. If the surface is given a grain effect and the skin is worked grain side down, as above described, and allowed to dry in contact with the surface, the pattern or surface of the support will be permanently impressed on this grain side of the leather. Moreover, this surface character will be substantially 25 uniform throughout the skin, whereas by the present method of "boarding," the fineness of the impression varies in the different 30 parts of the skin.

What I claim is:—

35 1. The process of treating leather, consisting in dampening the same with an adhesive and spreading the same over a plane surface with the grain side down, manually working the thicker portions of the leather 40 toward and into the thinner portions to effect a standardizing change in the thickness of each, and leaving the leather to dry as thus worked into position and held to the 45 plane surface by the mucilaginous substance.

2. The process of treating leather, which consists in working the flesh side of a mucilaginous coated hide so as to diminish the thickness of those portions of the hide adjacent the relatively thin flank portions thereof in favor of such flank portions, forcing the grain side of the hide as thus worked into adhesive contact with a plane surface, and allowing the same to dry while thus held. 55

3. The process of treating leather, which consists in wetting the same with an adhesive substance, and forcing the grain side thereof into uniform adhesive contact with a plane surface and working all parts of the 60 exposed flesh side into substantially uniform thickness, and allowing the same to dry while thus held in position.

4. The process of treating leather, consisting in drawing the same over an adhesive coated plane surface with the flesh side exposed, manually working the thicker portions of the hide over and into the adjacent thinner portions thereof to effect substantial uniformity in the thickness of the 65 entire hide, and forcing the grain side of the leather as thus worked into adhesive contact with said coated plane surface, and allowing the same to dry while thus held. 70

5. A dried, tanned hide or skin, having a 75 surfaced grain side, the thinner portions of the hide being thickened so that the hide is of more uniform thickness than the natural hide, substantially as described.

6. A tanned and dried skin or hide, having 80 its grain side surfaced throughout, the thinner portions of said hide or skin being worked into thickened condition, substantially as described.

In testimony whereof I sign this specification in the presence of two witnesses.

CARL E. SCHMIDT.
